CLAIM

The ornamental design for an outer housing for a light emitting diode strip assembly attachable to an architectural surface, as shown and described.

DESCRIPTION

FIG. 1 is a top, front, right side perspective view of an outer housing for a light emitting diode strip assembly attachable to an architectural surface, showing my new design; FIG. 2 is a front elevation view thereof, the back elevation view being a mirror image thereof;

FIG. 3 is a right side view thereof, the left side view being a mirror image thereof;

FIG. 4 is a top plan view thereof;

FIG. 5 is a bottom plan view thereof;

FIG. 6 is a top, front, right side perspective view thereof, shown in a state of use;

FIG. 7 is a front elevation view thereof, shown in a state of use;

FIG. 8 is a top, front, right side perspective view thereof, shown in a state of use; and,

FIG. 9 is a front elevation view thereof, shown in a state of use.

The broken lines illustrating symbolic break lines illustrate boundary lines and form no part of the claimed design. The remaining broken lines illustrate environmental structure and form no part of the claimed design.
